FOUNDATION GARMENT FOR WOMEN

Joseph Leonard, Allentown, Pa., assignor to
 Charis Corporation, New York, N. Y., a corporation of New York

Application September 30, 1936, Serial No. 103,245

7 Claims. (Cl. 2—30)

This invention relates to foundation garments for women wherein such support is given to the figure that its graceful and hygienic line of contour is maintained in sitting as well as in standing position.

While the normal inward curve of the back at the waistline is one of the characteristics of the figure which gives grace and beauty, its importance to health is so well recognized in the medical profession that it is stressed even in the most elemental textbooks on physiology. The slouching sitting posture with the lumbar curve straightened or reversed not only tends to bring about or prolong many of the spinal and sacroiliac ailments arising from misplacement of the bony structure with the nervous disorders incidental thereto, but is likely to result in organic troubles perhaps more especially with women than with men.

One of the objects of this invention is to provide a foundation garment which tends to prevent a slouching position in sitting and to maintain the lumbar curve in both standing and sitting positions while at the same time serving its purpose as a foundation garment in giving to the figure or maintaining therein lines of grace and beauty to accord with artistic requirements.

In sitting position there occurs a relaxation of certain of the shoulder and chest muscles supporting the upper ribs and shoulder blades and of the so-called skin muscles (platysma myoides) extending downwardly from the neck which contribute to the support of the breasts. This relaxation causes a slight drooping forward of the shoulders and a tilting downward of the bustline (the horizontal line from the tip of the breasts back through the figure) in sitting position.

One of the objects of this invention is to provide a support for the breasts which will permit of this normal slight drooping forward of the shoulders and tilting downward of the bustline in sitting position and which will at the same time co-operate with the other features of the foundation garment in maintaining the lumbar curve.

The normal slight drooping forward of the shoulders in sitting position where a corset of the ordinary type is worn, especially if the corset is provided with boning, results in the upper rear edge of the corset protruding and breaking the line of the outer garments in a very unsightly manner.

One of the objects of this invention is to provide a structure which prevents the rearward protrusion of the top of the garment when the wearer is in sitting position.

Coincident with the slight drooping forward of the shoulders and the tilting downward of the bustline in sitting position the muscular structure of the buttocks and lower back is considerably extended both vertically and laterally. 5 Present-day corsets for the most part extend well below the buttocks with the boning curved inwardly at the bottom, and in assuming a sitting position this muscular extension pulls downwardly the corset along the waistline and upper 10 back, causes an unhygienic and discomforting pressure on the breasts and tends to prevent the normal slight drooping forward of the shoulders and the tilting downward of the bustline as above set forth. 15

One of the objects of this invention is to provide for the drawing down of the corset in assuming sitting position without interfering with the normal slight drooping forward of the shoulders and the tilting down of the bustline and in so 20 doing to construct the garment in such a way as to tend to maintain the lumbar curve in both standing and sitting positions as heretofore referred to.

Another object of this invention is, while preserving and providing for the objects heretofore specified, to provide a boning reinforcement of the garment structure at the back which will bridge the waistline and will tend to keep the lower part of the shoulders in vertical alignment 30 with the rearward extremities of the buttocks. 25

Further objects of this invention will become apparent without specific mention as the disclosure hereof proceeds.

In carrying out the objects of the invention I 35 have developed a novel combination corset brassière in which what may be termed the corset member terminates in the front and sides slightly below the lower borderline of the breasts and in the back extends to a position well above the 40 waistline and preferably to a line approximately midway between the top of the ilia and the lower margin of the scapulae, with variations preferably above that line rather than below it. The corset member at the back is preferably provided with boning which spans the waistline and extends upward substantially to the top edge of the back portion. The back portion is, however, so constructed as to exert little or no pressure laterally on the breasts or across the chest wall 50 immediately beneath the breasts. 45

The brassière member of the garment encircles the body with its lower border likewise well above the waistline. It overlaps the back of the corset member in both standing and sitting positions 55

of the wearer and has vertical movement relative to the back portion of the corset member to accommodate the various postures of the body so that the upper portion of the back in the 5 lower dorsal or thoracic vertebral region is supported in proper position by the cooperative action of both the brassière and corset members.

In the front the brassière member is provided above with the usual breast pockets, beneath 10 which it encompasses the upper part of the dia- phragm and the region immediately below the breasts. In point of structure in the front the brassière member may conveniently be made integral with the corset member and this unity of 15 structure may or may not characterize the side portions of the brassière member and corset member toward the front. In either event, pivotal connections are provided between the brassière member and the corset member, one on 20 each side at the bottom of the brassière member either at the sides of the garment or slightly to the rear thereof, depending on the points of permanent attachment of the brassière member to the corset member. It is about these pivotal 25 connections that the brassière member moves in accommodating itself to the various positions of the breasts and body, in standing, bending and sitting; and it is by reason of these pivotal connections that the brassière and corset members 30 are maintained in their proper relation regardless of the position of the body. The brassière member is provided with shoulder straps in the usual manner.

The structure and proportions of the parts are 35 such that in standing and sitting positions and in the various postures in going from the one position to the other, the support of the foundation garment as a whole is continuous and unbroken, and while the brassière member tilts 40 about its pivotal attachments in accommodating the various positions and postures of the body, this support of the foundation garment is not lessened or weakened thereby.

I am well aware that combination corset brassières as such are very old in the art which furnishes many examples of foundation garments of this general classification which are divided across the front or across the back or both. These prior art garments, however, in no case known to me accomplish the objects above set forth, nor are they characterized by the structure of my invention hereinabove generally explained. In 50 many cases the corset member terminated approximately at or below the waistline so that there was a break in the support for the back of the wearer at the point where the support is most needed, from the standpoint of both proper posture and good lines. If boning were employed the upper ends of the boning tended to press into 55 the back of the wearer and cause great discomfort. The tilting of the bustline on assuming sitting position in its relation to the lumbar curve was apparently never before appreciated in corset construction, with the result that the brassière member was either firmly attached to the 60 corset member throughout the front and side portions of the corset well toward the back thereof, so that the pivotal movement above set forth was impossible, or was merely attached to the 65 front of the corset member with the back of the brassière member having no functional relation whatever with the supporting characteristics of the back portion of the corset member. My invention should not, therefore, be confused with 70 the examples of the prior art just set forth.

In the drawings which form a part of this application, I have illustrated two forms of combination corset brassières embodying the various characteristics of my invention above set forth. The drawings, however, are intended for illustrative purpose only and no limitations on the invention should be construed therefrom either in respect to the details of construction of the two particular garments shown or as to those 5 garments as types. In these drawings,— 10

Figure 1 is a front elevation of one form of garment embodying my invention with the wearer in standing position;

Fig. 2 is a rear elevation of the garment of Fig. 1, with the wearer in standing position; 15

Fig. 2a is a view corresponding with Fig. 2 and shows in rear elevation the second form of garment embodying my invention hereinbefore referred to; and

Fig. 3 is a side elevation of the garment of Fig. 20 1, with the wearer in standing position and with the upper arms of the wearer in substantially horizontal position;

Fig. 3a is a view corresponding with Fig. 3 and shows in side elevation the garment of Fig. 2a. 25

Fig. 4 is a side elevation of the garment of Fig. 1, with the wearer sitting and with the upper arms of the wearer in the position of Fig. 3;

Fig. 5 is a front elevation of the garment of Fig. 1, with the wearer in sitting position and 30 the arms relaxed in substantially vertical position;

Fig. 6 is a perspective of the garment of Fig. 1, showing a rear side view with the wearer in sitting position and the arms relaxed with the hands 35 resting on the knees;

Fig. 7 is a view similar to Fig. 6 with the brassière member of the garment of Fig. 1 cut apart vertically near the center line of the back to show the upper part of the corset member and 40 to illustrate the failure of support afforded by the upper part of the corset member in the absence of the cooperating action of the brassière member;

Fig. 8 is an elevational view of the garment 45 modeled in the first seven figures opened out and showing the interior of the garment;

Fig. 9 is a detailed view illustrating the particular type of pivotal connection between the brassière member and the corset member employed in the garment of Fig. 1; 50

The standing figures in the front and rear views are turned slightly to the side for clearness of illustration.

Referring more particularly to the drawings, 55 the garment illustrated in Figs. 1 to 9, inclusive, and its operation will first be described in detail.

The corset member

The corset member A in general construction 60 follows more or less conventional lines except as to its upper portion above the waistline indicated by the dot and dash line b—b. Thus, the corset member is composed of a series of strips of fabric and elastic sewed together and bound 65 with taping as is customary in the modern art of corsetry, with stocking supporters attached to the lower border and being sufficiently long to encompass the buttocks and the upper portion of the thighs, so that in sitting position the corset member extends forwardly beyond the points of the ischia and is firmly maintained in position by the weight of the wearer. 70

More particularly, the back of the corset member is formed with a center panel of fabric 10 and 75

two side panels 11—11 firmly stitched thereto. The side portions of the corset member comprise each an elastic strip 12 which extends from the top to the bottom of the corset member and is 5 stitched to the fabric panel 11 of the back, and a fabric strip 13 which is stitched on the one side to the elastic strip 11. One of the side portions is stitched to the front of the corset member, and the other is provided with a reenforced underlying and projecting band 14 to constitute the fastening edge of the corset member, eyes 15—15 being provided at suitable intervals along the edge of the fabric strip 13, the particular garment shown being a side opening garment.

15 The front of the corset member comprises a center panel of fabric 20 conveniently made of two vertical strips as illustrated, permanently stitched together and at the bottom provided with a triangular elastic gusset 21 extending approximately one-third of the distance from the bottom to the waistline. The center panel at the top merges into and comprises the lower center part of the brassière member. On each side of the center panel is another panel of fabric 22 20 which is firmly stitched to the center panel on the one side. On the other side one of the said panels 22 is stitched to the fabric side strip 13 as just above stated, and the other of said panels 22 provided with an underlying band 23 to 30 which is attached the hooks 24 which cooperate with the eyes 15—15 in fastening and unfastening the corset member.

The seams by which the various portions of the corset member are attached together are bound 35 with tape when desired in the usual manner, and there is a binding of tape along the top and bottom of the fabric portions.

The stocking supporters 30 are attached to the bottom of the corset member in connection with 40 the binding, two at the back, two at the front, and one on each side.

The upper part of the corset member above the waistline b—b, though following present-day manufacturing practice, differs radically 45 from other garments known to me. While its construction and form are such as to cooperate with the brassière member of the garment in affording the support to the back of the wearer and in maintaining its proper contour as above 50 set forth, the back portion of the corset member is so related to the front portion thereof as to avoid lateral pressure from the corset member itself across the breasts and the upper chest wall immediately beneath the breasts.

55 In furtherance of the avoiding of such lateral pressure, the upwardly extending portion of the back is centrally provided with a notch 35 and the sides of the corset member (the two strips, one of elastic 12 and the other of fabric 13 comprising each side) are cut away downwardly as at 36 from their upper point of attachment to the back to points below the line of the chest wall immediately beneath the breasts. From the junction of the front portion of the corset member with the fabric strips 13 of the side portions (by stitching on the one side and by the hook and eye attachment means on the other), the front panels 22 slope upwardly as at 38 to their point of attachment to the center panel 20.

70 The upwardly extending portion of the back of the corset member terminates in the lower dorsal or thoracic vertebral region of the back, slightly above the midway line between the tip of the ilia and the lower margin of the scapulae, as above 75 set forth.

The cut away fabric portions of the back and sides of the corset member just described have their edges suitably bound as is desired.

The center panel 20 of the front of the corset member extends upwardly above the panels 22—22 5 and is formed on its upper margin with curves 40 which terminate centrally in a point lying between the breasts. This upper margin of the panel is attached to the bottom of the breast pockets, later to be described, by suitable stitching.

The corset member is preferably provided with adequate boning to reenforce the supporting and figure-forming functions of the garment as a whole. While the amount of boning is somewhat 15 dependent on the design and size of the garment, the preferred boning in the style of garment shown in Figs. 1 to 9, inclusive, is as illustrated. In the back portion of the corset member at the extreme edge of the panels 11 where the back 20 portion is joined to the side portions, the bones 45—45 are placed. At the extreme edges of the center panel 10 where that panel is attached to the panels 11 the bones 46—46 are placed. These bones 45 and 46 extend downwardly partially to overlie the buttocks but the bones 45 for comfort in side bending may not extend downwardly to quite the distance of the bones 46. At the top the bones 45 and 46 extend to as near 30 the top of the back portion of the corset member as is practical. The boning in the front comprises the two bones 47—47 which are mounted one on each side of the vertical central line of the center panel 20 about midway between that line and the outer edges of the panel. These 35 bones extend downwardly to a line sufficiently above the groin to avoid discomfort in sitting and walking and upwardly to a line approximately joining the upper edges of the front panels 22—22 at their junction with the center panel. 40

The conventional bone pockets are provided on the inner side of the corset member for the bones above specified, and the bones are preferably suspended in these pockets by stitching 50 across tape 51 firmly attached to the upper extremity 45 of the bones.

The brassière member

The brassière member C comprises in front the breast pockets 60 of conventional two-ply woven 50 material, such as netting and lace, given the desired shape and contour by cutting and tape in the usual way, and a back band of fabric 62 attached to the sides of the breast pockets which embraces the sides and back of the figure and encircles the 55 upper part of the back and side portions of the corset member in both sitting and standing positions of the wearer.

The back band 62 is preferably made to conform to the lines of the figure of the wearer at the 60 back and sides when the wearer is in correct position, slightly idealized when desired or necessary. This fitting and conformation of the back band ordinarily requires the making of the same from a number of pieces of material. As illustrated, that 65 part coinciding with the back of the corset member is formed of two fabric pieces 63, preferably tapering down from the sides and suitably stitched along their edges at the middle and bound as illustrated. That part of the back band which coincides with the sides of the corset member comprises fabric strips 64 and triangular gussets of elastic 65 with the base of the triangles at the bottom of substantially the same dimension as the width of the elastic side strips 12 at the top. 70 75

These side pieces 64 are attached to the back portions of the back band and to the breast pockets by stitching and taping in the usual way. The side pieces 64 at the front extend below the breast pockets vertically and to these lower extensions are attached forwardly extending fabric pieces 66 (conveniently termed "frontal side fabric portions") which overlie the panels 22 of the corset member and have their inner ends attached to the edges of the center panel 20 by suitable stitching and their upper margins (curved to constitute lateral extensions of the curves 40) attached to the bottom of the breast pockets by suitable stitching. Between the front edges of the extensions 64 the lower part of the brassière member is completed by the upper portion of the corset member panel 20, as above explained.

The brassière member is illustrated as side opening in the same manner as the corset member. One of the side members 64 at its outer edge is provided with a reenforced underlying and projecting band 14' to constitute one of the fastening edges of the brassière member, eyes 15' being provided at suitable intervals along the edge of the fabric strip. The cooperating hooks 24' are attached to the edge of the correspondingly located breast pocket 60 and forwardly extending piece 66, suitably reenforced. The hook and eye opening of the brassière member is for convenience preferably on the same side as the hook and eye opening of the corset member, but slightly to one side or the other thereof to avoid superimposition of the reinforcements and hooks and eyes. In the garment shown the opening of the brassière member lies slightly to the rear of the opening in the corset member. For convenience the line of opening of the corset member is designated by the reference numeral 68 and the line of opening of the brassière member by the reference numeral 69.

Pivotal attachment of corset and brassière member

The pivoting of the brassière member of the garment to the corset member to accommodate the slight drooping forward of the shoulders and the tilting of the bustline in sitting position is illustrated at the bottom of the side portions of the back band of the brassière member, which is there fastened to the sides of the corset member above the waistline in suitable manner to provide for a tilting of the brassière member about this fastening as is required. As constructed in the garment of Figs. 1 to 9, inclusive (see Fig. 9), this fastening means comprises two loops of tape, the one 72 being suitably attached to the lower edge of the side strip 64 of the brassière back band, the other 73 being suitably attached to the upper edge of the fabric strip 13 of the side of the corset member, the said loops of tape encircling a metallic ring 74. This form of pivotal fastening is optional. Any suitable pivotal connection may be employed, as, for example, a single strong piece of tape such as illustrated in the form of garment shown in Figs. 2a and 3a, later to be described.

The pivotal attachment of the back band of the brassière member to the corset member at its sides comprises the only functional fastening of the back band to the corset member, and while affording the requisite relative movement between the brassière member and the corset member for the purposes herein set forth also serves as a means for maintaining the back band and corset member together in their relative positions, whatever the posture. Cooperating with this are the

conventional shoulder straps 76 which are attached to the top of the brassière portion at suitable points.

Loose motion connection of corset and brassière member

When the garment is not being worn the back band of the brassière member is quite likely to be moved so completely out of position that time is wasted and the patience tried in putting the garment on unless additional means are provided for fastening the back band of the brassière to the corset member, and to this end I provide a loose motion connection between them. A suitable loose motion connection for this purpose comprises on each side a strip of tape 79 which is fastened to the top of the corset member to overlie a considerable portion of the back panel 11 and elastic strip 12, beneath which is threaded a cooperating tape 80 which is fastened to the back band at the bottom near the elastic gusset 65 and extends diagonally forward to about the top of said elastic gusset where it is again fastened.

Operation

In addition to the waistline of the garment b—b above referred to, in taking the photographs from which the first seven figures are made, the dot and dash line d shown in Figs. 4, 6 and 7 was drawn on the corset member of the garment to mark the lower edge of the back band in standing position of the wearer. These lines will be referred to in describing the operation of the garment.

Assuming that the garment is properly donned by the wearer and that the wearer is in standing position as shown in the first three figures of the drawings, the corset member of the garment, with its boning reenforcement above described, and the form-fitted brassière member closely embracing the upper part of the corset member with its overlapping portions, offer a support for the figure which tends to enforce the correct standing posture both respecting the lumbar curve and the position of the upper back and shoulders. The breasts are held high and comfortably supported and the bustline as above defined is horizontal. The unbroken support of the corset member at the back extending as here illustrated to a position slightly above the midway line between the upper ends of the ilia and the lower margin of the scapulae and completely covering the region of the lumbar curve cooperates with the back band of the brassière member in the easy maintenance of this correct standing position.

As the wearer leans forward in passing through the series of postures from a standing position to a sitting position, the back departs but slightly from its contour in standing position, as the forward inclination in assuming the sitting position is primarily about the hip joints. Whatever deviation there may be, however, from the contour of the back in standing position is provided for by the tilting movement of the brassière member about its pivotal mounting 74—74.

When the wearer assumes sitting position, however, on the one hand, the slight drooping forward of the shoulders and the tilting downward of the bustline is accompanied by a pivotal movement of the brassière member around its pivotal points of attachment to the corset member, and on the other hand, the muscular extension of the buttocks draws downwardly the corset member at the back beyond the pivotal connection with the brassière member, so that from this pivotal

connection to the center vertical line of the garment at the back there is an increasing relative movement of the brassière and corset members, the brassière member moving upwardly and the 5 corset member moving downwardly. The tilting of the brassière member about its pivotal point of attachment with the corset member is well illustrated by a comparison of Figs. 3 and 4 wherein in the sitting position in Fig. 4 the hook 10 and eye line 69 of the brassière member has taken on a decided angular position in respect to the substantially vertical hook and eye line 68 of the corset member, these two lines being practically parallel in the standing position of Fig. 3. The 15 drawing downward of the corset member in sitting position is seen by a comparison of the waist-lines b of Figs. 3 and 4. The relative movement of the brassière and corset members in sitting position is perhaps best illustrated by noting the 20 position of the line d in Figs. 4 and 6 which as just stated is coincident with the lower margin of the brassière member in the standing position of Figs. 2 and 3.

The pivotal movement of the brassière about its 25 pivotal points of attachment, the drawing downward of the corset member, and the relative movement of the brassière and corset members are effected, however, without loss of support for the breasts and the back in the lumbar region and in 30 the lower dorsal or thoracic vertebral region. On the contrary, the breasts are supported in their slightly lowered position with the downward tilting of the bustline, the degree of curvature of the lumbar region proper to sitting position is maintained, and the torso is erect with no crowding 35 of the organs in their abdominal cavity. As seen in Figs. 4 and 6, the back band of the brassière member still closely encircles the upper part of the corset member and cooperates therewith in 40 maintaining a reenforced support to the very top of the back and side portions of the corset member.

Furthermore, by reason primarily of the cut down upper borders 36 of the side panels, no lateral pressure is exerted on the chest wall immediately below the breasts across the nerve center, popularly referred to as the pit of the stomach, which would tend to cause the wearer to assume a slouching position while sitting. The pivotal 50 movement of the brassière member provides for a uniformity of support for the breasts and of pressure across the chest wall immediately beneath the breasts, which would not be true if this support and pressure were exerted by the corset member. At the same time the snug fitting of the brassière member about the figure and about the upper portion of the corset member prevents the possibility of the upper portion of the corset member protruding rearwardly from the back of 55 the wearer should the wearer stoop forwardly while sitting or standing.

In sitting from standing position the back band of the brassière member slides smoothly and without appreciable effort upward on the upper part 60 of the back and sides of the corset member, but never separates therefrom, always giving continuity of support. In standing from sitting position this motion is reversed with the same 65 smoothness and without any displacement whatsoever of the upper part of the back and sides of the corset member, the parts assuming their correct interrelation and positions illustrated in Figs. 1 and 3. This relative movement of the two constituent members of the garment is effected with- 70

out any sliding of the brassière member on the skin of the wearer in properly fitted garments.

The cooperative functioning of the brassière and corset members of the garment are well illustrated by a comparison of Figs. 6 and 7. In Fig. 7 5 with the model maintaining her position of Fig. 6 the brassière member was severed to the left of the center seam of the back band as shown at 90. This immediately withdrew the effective support 10 of the breasts which forthwith sagged or drooped 15 raising perceptibly the back band of the brassière member at the back by pulling upwardly on the shoulder straps there attached. With the sagging of the breasts, the figure itself sloped forwardly, straightening in large part the lumbar curve so 20 that the back moved forwardly away from the upper portions of the corset member above the waistline. The supporting function of the back of the garment above the waistline was completely destroyed and the graceful, hygienic posture of Fig. 6 was lost.

The elastic portions of the garment illustrated give flexibility to the garment, add greatly to the 25 comfort of the wearer and provide for a freedom of body movement which is consistent with the primary objects and operation of this invention. They may or may not be present in their entirety as desired. In the particular garment illustrated in Figs. 1 to 9, inclusive, however, the placing of the elastic gussets 65—65 preferably in line with 30 and above the elastic strips 12—12 of the side of the corset member is functional in that on stretching the fabric back 63—63 of the back band is maintained in line with the fabric back of the 35 corset member, which alignment tends to prevent any engagement of the parts which would interfere with or preclude the smooth reciprocating vertical movement of the brassière and corset members.

The garment illustrated in Figs. 2a and 3a, a 40 side opening garment, departs from the garment illustrated in Figs. 1 to 9, inclusive, primarily in the construction of the sides and back, the front of the garment being identical with the front of the first form except in the particulars now to be 45 referred to, the difference being so minor and readily described that no front view of the second form of garment is given. As to the front of the second form of garment, Fig. 1 may, therefore, be conveniently considered in connection with Figs. 50 2a and 3a.

The corset member A' has a center panel 20' which, like the center panel 20 of Fig. 1, is a two-piece panel provided at the bottom with a triangular insert like the insert 21 of Fig. 1, and at the 55 top is merged into the lower central part of the brassière member C' preferably without break in the fabric, precisely as shown in Fig. 1. The side panels 22' of the front are identical with those of the garment of Fig. 1 at the bottom, but at the 60 top they continue upwardly to the lower border of the breast pockets 60' to which they are attached by stitching in suitable manner, their upper parts, therefore, merging into and forming the side 65 front parts of the lower portion of the brassière member preferably without break in the fabric. The boning reenforcement in the front of the corset member of the first form of garment may be employed in the second form. The front of 70 the brassière member has breast pockets 60' to which are suitably attached shoulder straps 76', the breast pockets and shoulder straps being identical with those of the first form. As is apparent from Figs. 2a and 3a the lower part of the 75

brassière member does not have the forwardly projecting pieces 66 of the form of Fig. 1.

The sides of the garment illustrated in Figs. 2a and 3a, like the sides of the first form of garment (see Figs. 2 and 3), are each formed with two vertical pieces 12' and 13'. The forward pieces 13' which are of fabric differ from the corresponding pieces 13 in the first form in that they extend preferably in unbroken structural line to the top 10 of the brassière member functionally merging into and forming a part of that member. The side piece 13' on one side is stitched to the side of its corresponding front panel 22' and breast pocket 60' throughout its length. The side piece 13' on the other side is provided with an underlying band 14' from top to bottom above which at the 15 edge of the side piece are attached eyes 15' which cooperate with hooks mounted on the underside of the outer edges of the corresponding side piece 20 22' and the breast pocket 60', which edges are reenforced with an underlying band, all as will be understood from the more elaborate description and showing of the similar parts of the first form of garment.

25 The rearward pieces 12' of the side of this garment differ from the corresponding side pieces 12 of the first form in that they are of fabric rather than of elastic and extend slightly further to the back of the garment. The side pieces 12' continue upwardly above the waistline *b* where they form the side pieces of the upwardly extending back portion of the corset member, being cut diagonally downward from the top on each side as indicated by the dotted line 33' to points well 30 above the waistline but terminating sufficiently below the chest wall immediately beneath the breasts so that no pressure is there exerted by the corset member itself. As illustrated in Figs. 2a and 3a these side pieces 12' for purposes of proper fitting may be formed of two pieces stitched together on the diagonal across the waistline where they form a suitable attachment means for the double ply pivoting tapes 74' which replace the tapes 72, 73 and the link 74 of the first form illustrated in detail in Fig. 9. At the bottom and to the rear of each of the side pieces 12' there are 35 triangular inserts of elastic 12''.

The back of the corset member is substantially identical with that of the first form, being composed of a center panel 10' to each side of which are the panels 11'. These panels are of fabric and extend from the bottom of the corset to the top of the upwardly extending portion of the back which is substantially of the same shape and proportion as the upwardly extending back portion of the first form. The reenforcing boning 45' and 46' of the second form corresponds in method and place of attachment, form and size with the boning 45 and 46 of the first form. The center piece 10' and side pieces 11' are, however, somewhat narrower than those of the first form due to the fact that the side pieces 12' extend further to the rear than the side pieces 12 of the first form. Furthermore, the upwardly extending portion 40 of the back, while cut slightly downward from the top of the side pieces 12' toward the center and not having the distinctive notch 35 of the first form, terminates above at substantially the same distance from the waistline as the upwardly extending back portion of the first form. The back and side pieces are stitched together and their margins bound with tape in the usual form as will be readily understood.

In the second form only four garters 30' are 45 illustrated, these being two in the front and one

on each side. This, however, is purely a matter of preference.

As to the brassière member the back band 62' at each side terminates at the rear edge of the upward extensions of the side pieces 13' to which 5 its side pieces 64' of fabric are attached by stitching and tape in the usual manner. The back of the brassière member is formed of two pieces of fabric 63' stitched at their outer edges to the side pieces 64' and to each other at the center, a triangular gusset 65' of elastic being provided midway at the top. The top line of the back band which slopes gently downward from the sides to the elastic gusset terminates in the lower dorsal or thoracic vertebral region of the back 15 well above the top of the upwardly extending back portion of the corset member and slightly higher than the back band of the first form. The lower line of the back band terminates well above the waistline. Its center back portion is 20 curved gently upward and its side pieces extend upward at quite a perceptible angle. The shoulder straps 76' are suitably attached to the upper edge of the back band of the brassière member.

The pivotal attachments of the back band of 25 the brassière member to the corset member which as heretofore stated are formed merely by the two-ply tapes 74' are placed slightly further to the rear on each side than are the pivotal attachments of the first form. The tapes 74' are at 30 attached to the back band as here shown spanning the seams between the side pieces 64' and the back pieces 63'.

The second form of garment may be provided with a loose motion attachment between the 35 corset and brassière member similar to that (79, 80) employed in the first form.

The back band of the brassière member overlies and cooperates with the upwardly extending back portion of the corset in sitting, bending and 40 standing positions of the wearer, and the entire operation and functional performance of the second form of garment is identical with that of the first form of garment. It is believed that this operation and functional performance will be well 45 understood from the foregoing described operation of the first form of garment without repetition.

While the pivotal connection of the back band 50 of the brassière member to the back of the corset member in the second form is quite different from the pivotal attachment of the two members in the first form and the points of attachment are located considerably closer to the back, the pivotal action of the brassière member in both 55 forms keeps the disconnected portion of the brassière member in position and assures the maintenance of the bust in its normal position when the wearer is standing, bending or sitting. It allows the breasts to droop normally as a result of 60 the relaxation of the muscles in sitting position and to return to their normal position when the wearer resumes a standing posture without at any time depriving the breasts of the desired support. This pivotal action, together with the fact that 65 the breast pockets and the portion overlying the diaphragm are structurally independent of the back portion of the corset member and not subject to the pull and strain exerted upon the back portion of the corset member through the various 70 changes of posture, is of great importance to the wearer both from the standpoint of comfort and artistic lines. This is particularly true during any period of fashion such as obtains on the filing date hereof, which demands the molded bust and 75

the uplift effect necessitating a very snug fitting garment under the breasts.

It should be apparent from the foregoing that my invention is not limited to the foundation garments herein above described either as to the type of the garment or as to the details of construction. The invention is, for example, very useful in garments embodying the improvements set forth in U. S. Letters Patent No. 1,978,092, granted October 23, 1934. The garments here shown were selected from a number of different types embodying the invention because of their simplicity for illustrative purposes and no undue limitation should be deduced therefrom, but the appended claims should be construed as broadly as permissible in view of the prior art.

Having thus described my invention, what I claim is:

1. In a foundation garment for women, the combination of a figure-conforming corset member and a figure-conforming brassière member overlying the top of the corset member at the sides and back thereof in sitting and standing positions of the wearer, the brassière member being permanently attached to the corset member at the front and being pivotally connected to the corset member at the sides so that relative movement between the brassière member and the corset member about the pivotal mounting is provided for to accommodate the relative lowering of the breasts in sitting position, the corset member at the back extending in vertical unbroken lines over the region of the lumbar curve to a point well above the waistline in sitting and standing positions and cooperating with the brassière member in tending to maintain the lumbar curve in both these positions.

2. In a foundation garment for women, the combination of a figure-conforming corset member and a figure-conforming brassière member overlying the top of the corset member at the sides and back thereof in sitting and standing positions of the wearer, the brassière member being permanently attached to the corset member at the front and being pivotally connected to the corset member at the sides so that relative movement between the brassière member and the corset member about the pivotal mounting is provided for to accommodate the relative lowering of the breasts in sitting position, the corset member at the back extending in vertical unbroken lines over the region of the lumbar curve to a point well above the waistline in sitting and standing positions and cooperating with the brassière member in tending to maintain the lumbar curve in both these positions, the corset member above the waistline being so constructed as to its upwardly extending portion at the sides and back that no lateral pressure is exerted therefrom on the breasts and chest wall immediately beneath the breasts.

3. In a foundation garment for women, the combination of a figure-conforming corset member and a figure-conforming brassière member overlying the top of the corset member at the sides and back thereof in sitting and standing positions of the wearer, the brassière member being permanently attached to the corset member at the front and being pivotally connected to the corset member at the sides so that relative movement between the brassière member and the corset member about the pivotal mounting is provided for to accommodate the relative lowering of the breasts in sitting position, the corset member at the back extending in vertical un-

broken lines over the region of the lumbar curve to a point well above the waistline in sitting and standing positions and cooperating with the brassière member in tending to maintain the lumbar curve in both these positions, the corset member at the back having its side members cut away at the top to a point below the lower line of the breasts and the chest wall immediately beneath the breasts so that no lateral pressure is exerted therefrom on the breasts and the chest wall immediately beneath the breasts.

4. In a foundation garment for women, the combination of a figure-conforming corset member and a figure-conforming brassière member overlying the top of the corset member at the sides and back thereof in sitting and standing positions of the wearer, the brassière member being permanently attached to the corset member at the front and being pivotally connected to the corset member at the sides so that relative movement between the brassière member and the corset member about the pivotal mounting is provided for to accommodate the relative lowering of the breasts in sitting position, the corset member at the back extending in vertical unbroken lines over the region of the lumbar curve to a point well above the waistline in sitting and standing positions and being there reenforced by boning on each side of the center line of the corset member which extends upwardly to substantially the upper margin of the back, the brassière member cooperating with said upwardly extending portions of the corset member at the back in tending to maintain the normal lumbar curvature in both sitting and standing positions, the brassière member holding the upwardly extending portion of the corset member at the back snugly against the body of the wearer in standing, bending and sitting positions and thereby maintaining smooth unbroken lines and preventing the said upwardly extending portions of the corset member from protruding from the back of the wearer.

5. In a foundation garment for women, the combination of a figure-conforming corset member and a figure-conforming brassière member overlying the top of the corset member at the sides and back thereof in sitting and standing positions of the wearer, the brassière member being permanently attached to the corset member at the front and being pivotally connected to the corset member at the sides so that relative movement between the brassière member and the corset member about the pivotal mounting is provided for to accommodate the relative lowering of the breasts in sitting position, the corset member at the back comprising a center panel and two side panels stitched to the center panel one on each side thereof all extending in unbroken vertical lines over the region of the lumbar curve to a point well above the waistline in sitting and standing positions, boning positioned along the outer margin of the said center panel and along the outer margin of the said side panels and extending upwardly to substantially the upper margin of the back, the sides of the corset member adjoining and being attached to the back thereof being cut away from the top downward to points located below the chest wall immediately beneath the breasts, the said boning reenforcing the unbroken vertical support of the back over the region of the lumbar curve, the cut away portions of the back and sides at the top preventing lateral pressure being exerted by the corset member across the breasts and chest wall immediately be-

neath the breasts, the corset member at the back above the waistline cooperating with the brassière member in tending to maintain the lumbar curve in both sitting and standing positions.

5 6. In a foundation garment for women, the combination of a figure-conforming corset member and a figure-conforming brassière member overlying the top of the corset member at the sides and back thereof in sitting and standing 10 positions of the wearer, the brassière member comprising breast pockets and a back band extending around the sides and back of the wearer, the corset member at the front having a center panel extending continuously upward to the lower 15 margin of the breast pockets, the back band of the brassière member having forwardly extending portions which at the top are attached to the lower extremity of the breast pockets and in the front are attached to the upwardly extending center panel of the corset member, means for pivotally attaching the back band of the brassière member to the sides of the corset member above the waistline so that relative movement between the brassière member and the corset member about the pivotal mounting is provided for to 20 accommodate the relative lowering of the breasts in sitting position, the corset member at the back extending in vertical unbroken lines over the region of the lumbar curve to points well above the waistline in sitting and standing positions and 25 cooperating with the brassière member in tending to maintain the lumbar curve in both these positions.

7. In a foundation garment for women, the combination of a figure-conforming corset member and a figure-conforming brassière member; the brassière member comprising in the front 30 breast pockets and a subtending fabric portion

suitably attached thereto, at the sides toward the front frontal side fabric portions suitably attached at their top edges to the breast pockets and at their front edges to said subtending fabric portion and having their bottom edges overlapping and relatively movable in respect to the corset member in standing, bending and sitting positions, said subtending fabric portion comprising an upwardly extending portion of the front of the corset member, and at the sides toward the back 10 and at the back a back band comprising side portions suitably attached to the said frontal side portions and a back panel connecting said back band side portions; the corset member at the back extending upward in vertical unbroken lines over the region of the lumbar curve to points well 15 above the waistline in the dorsal or thoracic vertebral region in standing, bending and sitting positions and being cut away at the sides to a point below the lower line of the breasts and the chest wall immediately beneath the breasts so that no lateral pressure is exerted by the corset member on the breasts and the chest wall immediately beneath the breasts; the back band of the brassière member being pivotally attached to 20 the corset member at the sides at points back of the said frontal side portions and overlapping the upwardly extending back portion of the corset member in standing, bending and sitting positions; the brassière member cooperating with the 25 corset member in maintaining the lumbar curve in standing, bending and sitting positions without subjecting the breasts to pull or stress; the construction and arrangement of the parts being such as to afford the breasts support and to tend 30 to maintain them in normal position in standing, bending and sitting.

JOSEPH LEONARD.
